MEANS FOR SEALING SHAFTS

Samuel F. Dupree, Jr., Shaker Heights, Ohio

Application October 2, 1936, Serial No. 103,757

1 Claim. (Cl. 286—11)

This invention relates to means for sealing the shafts of pumps or similar apparatus used for the circulation of fluids, and has for its general object to provide such shafts with efficient means for preventing the passage of fluid thereby. A further object of the invention is to provide such shafts with sealing means including a spring wherein the spring will be sealed against access of fluid thereto. A still further object of the invention is to prevent this access of circulating fluid to the spring without the necessity for employing sealing rings which are held in close engagement with the shafts with which they cooperate.

Further and more limited objects of the invention will be explained hereinafter and will be realized by the construction and arrangement of parts shown in the accompanying drawings wherein Fig. 1 represents a central longitudinal sectional view through a pump body and rotor or impeller having my sealing elements applied thereto, the elements being shown in elevation; Fig. 2 an enlarged detail in section through the sealing elements and the parts of the pump body and rotor associated therewith; Fig. 3 an elevation of one of the sealing elements; Fig. 4 an elevation of another sealing element; Fig. 5 a detail in front elevation and Fig. 6 a detail in section of one of the casing or cup members for the spring element; Figs. 7 and 8 are views, corresponding, respectively, to Figs. 5 and 6, of the other cup member; Fig. 9 is a view similar to Fig. 2, showing a modification of my sealing elements; and Fig. 10 is a view, showing a still further modification of the sealing elements.

Describing by reference characters the various parts illustrated in the drawings, and first with particular reference to Figs. 1-8 inclusive, 1 represents a pump body detachably secured to the wall 2 of a liquid-containing chamber, which may be the water jacket of an internal combustion engine. The pump body is shown as provided with a chamber 3 communicating with the water jacket and with an outlet 4 for delivering the water to the radiator.

The pump body is provided with a bore comprising an outboard cylindrical section 5 and an inboard cylindrical section 5^a of smaller diameter than section 5. 6 and 6^a denote bushings which are mounted, respectively, in the bore sections 5, 5^a, and 8, 8^a denote a shaft which is mounted in said bushings and which is provided at its outboard end with a hub 9 secured thereto by a pin 10, said hub having a flange 11 to which

the pulley 12 and fan 13 are secured, as by means of screw bolts 14.

15 denotes the rotor or impeller of the pump, the same having a hub 16 which is secured to 5 the shaft by means of a pin 15^a. It will be noted that the hub of the rotor is provided with a cylindrical chamber 17 extending thereinto from its outboard face, the said chamber having a bottom wall 18. The outboard end 16^a of the hub 16 is formed as an annular wall provided with slots 19 extending thereinto; and the adjacent central annular shoulder of the pump body projects thereinto, as shown at 20.

The pump body, with the bore sections 5, 5^a 15 and the bearing bushings 6, 6^a, is of a standard construction adopted by one of the leading makers of automobiles, as is the case with the shaft 8, 8^a. It will be noted that the section 8^a of the shaft is of greater diameter than the section 20 8, an annular shoulder 8^b being formed between the two sections. The inboard end of the bushing 6 abuts against the outboard face of a thrust ring 21, the inboard face of which ring abuts against the shoulder 8^b. The thrust ring is 25 driven by means of lugs 21^a projecting from said ring, the inboard ends 21^b of the said lugs projecting from the inboard surface of the ring and entering slots 8^c in the enlarged portion of the shaft adjacent thereto. This thrust ring compensates for thrusts such as may be exerted upon the shaft by the pulley 12 and the fan 13.

22 denotes a receptacle within the pump body from which lubricant is supplied between the bushings 6, 6^a and the shaft sections 8, 8^a by 35 means of ports 23, 23^a and 24, 24^a.

The sealing elements which cooperate with the annular shoulder 20 and the shaft and the chamber 17, 18 will now be described in detail.

40 25 denotes a sealing ring, which is preferably made of material known to the trade as Bakelite or "Micarta," having lugs 25^a entering the slots 19, whereby the said ring will be driven by the rotor or impeller. It will be noted that the inner cylindrical wall 25^b of this ring is spaced from the portion 8^a of the shaft which it surrounds. The ring 25 is yieldingly pressed against the annular shoulder 20 of the pump body by means of a coiled spring 26 and a ring of deformable resilient material engaged by said spring and within which the said spring preferably is located. The spring is mounted within a two-part metallic casing 27, 28 surrounding and spaced from the shaft, the casing in turn being mounted within a channel ring of deformable

resilient material. Each section of the casing comprises a cup having a radially extending wall 27^a, 28^a, respectively, and a cylindrical wall 27^b, 28^b, respectively, the wall 27^b being shown as telescopically mounted within the wall 28^b. The inner ends of the walls 27^a and 28^a do not contact with the adjacent shaft section 8^a and the end of the cylindrical wall 27^b which is remote from the wall 27^a is provided with a plurality of short radially outwardly extending walls 27^c separated by slots 27^d while the end of the wall 28^b which is remote from the wall 27^b is provided with a plurality of short radially inwardly extending walls 28^c and slots 28^d therebetween. By this construction, the casing sections may be assembled by passing the projecting walls 28^c through the slots 27^d and by thereafter giving a partial rotation to either or both of the casing sections, whereby the sections are detachably connected by a bayonet-joint construction.

The spring, with its enclosing two-part casing is inserted within a channeled sealing ring made of deformable and resilient material capable of withstanding the action of the liquid which is circulated by the rotor or impeller. For this purpose, I prefer to use in the construction of this ring a synthetic rubber composition known to the trade as "Duprene." 29 denotes the outer wall of the last mentioned ring and 29^a the radially inwardly extending side flanges or members thereof. Each of these flanges is provided with concentric corrugations 29^b.

The spring 26 having been inserted within its casing 27, 28, the spring and casing constitute a unit which can be inserted without difficulty within the ring 29-29^b. The ring 29-29^b with the spring and casing therein, is inserted within the chamber 17, 18, with the corrugated inboard flange of the ring 29 bearing against the wall 18 and the corrugated outboard flange bearing against the ring 25. When the sealing-ring assembly has thus been inserted into the chamber 17, 18, it can be retained therein by means of an outwardly expanding snap ring 30 mounted in a groove 31 within and adjacent to the outboard end of the hub 16.

When the impeller and pump body are assembled, as shown, the spring 26 will be compressed, as shown in Fig. 2, and the lugs 25^a will be within the slots 19 but between the inboard ends of the same and the ring 31, whereby the said ring may float as longitudinal thrusts are imparted to the shaft by the fan.

As the parts wear, the spring 26 expands, this movement being permitted by the telescopic connection between the cylindrical flanges of the casing sections and the elongation of the wall 29 of the "Duprene" ring until the walls 28^c and 27^c are in engagement. The amount of expansion permitted the spring by these casing members will be only sufficient to accommodate the maximum amount of permissible wear upon the sealing surfaces.

Inboard thrusts exerted upon the shaft 8, 8^a by the spring 26 will be compensated by the engagement of the inboard end of the hub 8 with the outboard end of the bushing 6, while outboard thrusts due to the fan 18 will be compensated by the thrust washer 21. The parts are so proportioned, constructed and arranged that, when the hub 8 and bushing 6 are in contact and the thrust washer 21 is in contact with the shoulder 8^b and the inboard end of the bushing 6, the lugs 25^a of the sealing ring 25 will be approximately midway of the length of the slots

19, thereby permitting the said ring to travel in either direction to compensate for wear upon the thrust surfaces.

In Fig. 9, there is shown a modification of the construction of the sealing elements shown in the preceding views. The portions of the pump body, shaft, and impeller which appear in Fig. 9 are identical with the portions of the same which are shown in the preceding views and are designated by the same numerals. The ring 25 is shown as bearing with its outboard face against the annular shoulder 20 provided at the inboard end of the pump body. However, instead of housing the spring 26 within a channeled ring consisting of a unitary body of resilient and deformable material, I house the same in a composite channeled ring comprising two side members or flanges 32 of deformable resilient material, such as "Duprene," the side members or flanges being constructed in the same manner as the side flanges of the Duprene ring 29-29^b and each having concentric corrugations 32^a, those on the inboard member or flange engaging the wall 18 and those on the outboard member or flange engaging the inboard face of the ring 25. The side members or flanges 32 are connected by a lengthwise expandible and contractible corrugated metal casing 33, similar to the bellows-like casings known to the trade as Sylphons. The radially inwardly extending ends 33^a are fitted within slots 32^b extending radially inwardly from the outer cylindrical surfaces of the side members or flanges 32. It is unnecessary to vulcanize the flanges 33^a into the slots 32^b, since the expansive effort of the spring 26 will be sufficient to maintain these slots closed. The opposite ends of the spring 26 are shown as bearing against the radially extending flanges 34 of angular retaining rings or washers, the cylindrical flanges of which engage the inner cylindrical surfaces of the members 32, thereby to limit the expansion or deformation of the said members toward the shaft. Similar retaining rings or washers may be used with the side flanges or members 29^a.

The composite channeled ring 32-33^a operates in the same manner as does the channeled ring 29-29^b in protecting the spring 26 from access of fluid, while the spring and the said composite ring also operate in the same manner as the spring 26 and ring 29-29^b in pressing the ring 25 against the shoulder 20 and in sealing the shaft and the interior of the channeled ring, as well as the spring, against access of fluid therebetween to the inner wall 25^b of the ring 25 and the shaft.

In Fig. 10 I have shown a still further modification of my invention wherein the ends 33^a of the expandible and contractible casing 33 are vulcanized to the outer cylindrical surfaces of the members 32. In all other respects, the construction shown in this view is identical with that shown in Fig. 9.

The two-piece casing and spring shown in Figs. 1-8 inclusive form an assembly which can be readily inserted into the ring 29-29^b which will retain the spring under a partial tension, and the ring, with the casing and spring therein can be kept in stock, ready for assembly when needed and without unduly expanding the deformable and resilient ring 29-29^b. When assembled in the environment shown in Figs. 1 and 2, the spring and the ring 29-29^b are compressed, while the parts of the casing are of sufficient length to accommodate all desirable wear up to

the time when the walls 27^c and 28^c are in engagement.

In all forms of my invention disclosed herein, the radially extending sides or flanges of the channeled ring which encloses the spring are provided with concentric corrugations. These corrugations are important in providing an effective seal against the passage of fluid radially inwardly between the sides and the surfaces which they respectively engage.

While I have shown my sealing means associated with one of the standard constructions of pump body and rotor or impeller now on the market, it will be obvious that the same can be used with other standard constructions including those wherein the chamber for the sealing elements is provided within the pump body and wherein the rotor is provided with an annular shoulder engaging the inboard face of the ring.

25. An example of this construction is shown 20 in my co-pending application Serial No. 98,220,

filed August 27, 1936, now Patent No. 2,157,597, issued May 9, 1939.

Having thus described my invention, what I claim is:

5 A composite sealing element comprising a longitudinally expandible and contractible channeled ring, a two-piece casing having radially extending side walls mounted within the sides of the said ring and having telescoping cylindrical walls, and a coil spring having its opposite ends engaging the side walls of said casing the end of the inner telescoping cylindrical wall having a plurality of spaced radially outwardly projecting walls and the over-lapping end of the outer telescoping wall having spaced radially inwardly projecting walls whereby the said casing sections may be assembled by a bayonet-joint movement and the projecting walls may limit the expansion of the spring.

SAMUEL F. DUPREE, JR.
